INVENTOR.

JOHN W. SMITH
BY *John W. Smith*
his ATTORNEY.

UNITED STATES PATENT OFFICE.

JOHN W. SMITH, OF PHILADELPHIA, PENNSYLVANIA, ASSIGNOR TO BUDD WHEEL COMPANY, OF PHILADELPHIA, PENNSYLVANIA, A CORPORATION OF PENNSYLVANIA.

METHOD OF ROLLING WHEEL DISKS.

Application filed March 31, 1926. Serial No. 98,661.

The invention relates to a process of rolling metal disks and more particularly to the process of rolling thin steel disks tapering from the center to the periphery such as are employed in the manufacture of vehicle wheels.

The broad process of which this process is an improvement and an apparatus for carrying out that process are fully disclosed and claimed in my pending application for process of and apparatus for forging metallic disks, Serial No. 408,231, filed September 4, 1920.

In the practice of the method disclosed in said prior application, a metal blank to be worked is placed upon a rotating platen, the surface contour of which, in cases where the disk is to be given a slight taper, has a slight concavity conforming to the taper it is desired to give the disk. It is then clamped or otherwise suitably held against rotation relative to the platen, and a pair of narrow-faced rolls are brought by relative approaching movement of the platen and rolls into engagement with the blank adjacent its center, and then traversed outwardly in opposite directions toward the periphery of the platen. In this outward movement, the blank is, by a combined rolling and spinning action, reduced in thickness and increased in diameter, and since the rolls travel in a direction at right angles to the axis of the platen, the disk is given a taper corresponding to the contour of the surface of the platen. This method can be used to reduce either hot or cold blanks.

If, in the practice of this method, the rolls were traversed outwardly, while in their operative relation to the platen and blank being worked, beyond the peripheral edge of the blank, it sometimes happened that waves or other irregularities were caused in the periphery of the disk, and this was especially true in the case of hot blanks. Sometimes, the heavy pressure of the rolls on the blank just as it was passing off the periphery of the blank caused the metal to be lapped, pleated or otherwise piled up in front of the rolls, which was liable to cause the displacement of the disk upon the platen with the possibility of spoiling the product.

In order to overcome this difficulty, the method forming the subject matter of the

present application was conceived. It was found that all tendency to lapping, pleating, waving, etc., could be avoided, even if the blank was rolled right up to the periphery thereof, by relieving the pressure of the rolls upon the disk just before the rolls had traversed beyond the periphery of the disk.

In the accompanying drawings the novel improved process is illustrated diagrammatically in various stages of the rolling operating by means of apparatus similar to that disclosed in my prior application hereinbefore referred to.

In the drawings:

Fig. 1 shows the relative position of a rotating blank support, the blank thereon and a pair of traversing rolls at substantially the beginning of a rolling pass in accordance with my improved process.

Fig. 2 shows the relative position of the parts in a second stage of the rolling process when the rolls have reached the periphery of the blank but are still in rolling contact therewith.

Fig. 3 shows the relative position of the parts in a third stage of the process as the rolls are passing out over the periphery of the disk and the pressure has been relieved by a relative separating movement of the disk and platen.

In the diagrammatic showing of an apparatus for carrying out the improved process of rolling a sheet steel disk, 10 represents a rotating support for the blank 11, which support is shown as having a slightly concaved surface corresponding to the taper to be given the finished disk, 11^a, Figs. 2 and 3.

12 and 13 are a pair of conical narrow faced rolls for cooperation with the surface of the platen in spinning and rolling a disk, the rolls and platen having relative approaching and separating movement and the rolls are mounted so as to permit their rotation while in contact with the work and while so in contact they are traversed radially outward, as indicated by the arrows, by any suitable means, (not shown). As shown in the drawings they are moved outwardly in opposite directions and on a line at right angles to the axis of the rotating platen 10.

With the apparatus disclosed, the improved process is carried out as follows:

While the rolls and platen are separated the blank to be rolled is placed on the platen and suitably centered and clamped or otherwise secured against relative rotation on the platen. If the platen is not already rotating, its rotation is started, and then by a relative approaching movement of the rolls and the platen, the rolls are projected against the blank adjacent its center and then traversed outwardly in spiral paths until they reach the periphery of the blank. In such movement from approximately the position shown in Fig. 1, to the position shown in Fig. 2 the blank is reduced in thickness and expanded radially to increase its diameter by a combined rolling and spinning action. When the rolls have reached the position shown in Fig. 2, substantially the entire surface of the blank has been subjected to the rolling action. While the rolls are still moving outwardly from the position shown in Fig. 2, the pressure of the rolls upon the disk is relieved by a relative separating movement of the rolls and platen, with the result that the working face of the rolls pass outwardly beyond the periphery of the disk out of rolling contact with the same, and hence, preclude the possibility of the formation of waves, pleats, laps, or other piling up of the metal of the disk at the thinned out periphery with a possible spoiling of the work.

The improved method of rolling in which the rolling proceeds from the central portion of the blank toward its periphery which includes the step of relieving the rolling pressure at the stage of the process when substantially the entire disk has been subject to the rolling action, by whatever means or apparatus it is accomplished, constitutes the essential novel feature of the invention, whereby a maximum speed of production may be achieved with a minimum of rejected disks.

What I claim and desire to secure by Letters Patent is:

1. The process of making tapered disks which consists in rolling a sheet metal blank of even thickness along a spiral line running from a point adjacent the center to the periphery, and relieving the rolling pressure

before the roll or rolls pass off the edge of the blank.

2. The process of making a thin disk of tapered cross-section from a sheet metal blank of even thickness which consists in concurrently rolling and spinning the metal of the blank radially outward to a progressively increasing degree and rolling circumferentially to a corresponding diminishing thickness the metal so spun, and relieving the rolling pressure before the roll or rolls pass off the edge of the blank.

3. The process of rolling disks which consists in placing the blank on a rotating support on which it is secured against rotation relative to the support, then subjecting it to the rolling action of outwardly traversing rolls whereby to concurrently reduce its thickness and increase its diameter, and terminating said rolling action before the rolls pass off the peripheral edge of the blank.

4. The process of making tapered disks which consists in rolling a sheet metal blank along a spiral line from a point adjacent to its center to the periphery whereby to reduce its thickness and increase its diameter, and relieving the rolling pressure just as the roll or rolls are about to pass outwardly beyond the periphery of the disk.

5. The process of making tapered disks out of a sheet metal blank of substantially even thickness which consists in subjecting the blank while rotating it to the action of a narrow-faced traversing roll to spin and roll the metal of the blank outwardly and in relieving the rolling pressure substantially at the instant when the roll is passing laterally beyond the disk.

6. The process of making tapered disks from sheet metal blanks of substantially uniform thickness which consists in subjecting the blank to the action of an outwardly traversing roll to roll the disk progressively from the center to the periphery, and in relieving the pressure of said roll after the complete disk has been subjected to its action but before it passes radially beyond the disk.

In testimony whereof he hereunto affixes his signature.

JOHN W. SMITH.
